UNITED STATES PATENT OFFICE.

JULIUS T. SENG, OF CHICAGO, ILLINOIS, ASSIGNOR, BY MESNE ASSIGNMENTS, TO GENEVA FURNITURE MFG. COMPANY, OF GENEVA, NEW YORK, A CORPORATION OF NEW YORK.

SOFA-BED.

No. 820,826.

Specification of Letters Patent.

Patented May 15, 1906.

Application filed November 14, 1904. Serial No. 232,638.

To all whom it may concern:

Be it known that I, JULIUS T. SENG, a citizen of the United States, residing at Chicago, in the county of Cook and State of Illinois, have invented a Sofa-Bed, of which the following is a specification.

This invention relates to improvements in sofa-beds, and particularly to that class of sofa-beds wherein there are comprised moveable seat and back sections hinged together at their meeting ends through the medium of a locking-hinge, the back-section being operated through a manipulation of the seat-section.

The objects of the present invention are to provide a cheap and simple construction of sofa-bed which when the same is withdrawn from the wall a slight distance may by an easy and convenient manipulation of the seat-section cause the latter to be advanced and the back-section simultaneously advanced and lowered into a plane with said seat-section, whereby the two coact or combine to constitute a comfortable bed, and, furthermore, by a reverse manipulation of said seat-section the same will be retracted within the frame and the back-section simultaneously retracted and reelevated to its normal position, whereby the article is reconverted into an ordinary sofa.

Various other objects and advantages of the invention will hereinafter appear, and the novel features thereof will be particularly pointed out in the appended claims.

Referring to the drawings, Figure 1 is a transverse vertical sectional view of a sofa-bed embodying my improvements, the same being illustrated in bed form. Fig. 2 is a similar view with the back-section lowered and advanced as in Fig. 1, the seat-section being elevated, so as to disengage the same from locking engagement with the back-section prior to a lowering of said seat-section. Fig. 3 is a similar view with the article shown in sofa form. Fig. 4 is a detail in elevation of the preferred form of locking-hinge employed between the seat and back sections, the hinge being shown in the position it will assume when the parts are in the relative position shown in Fig. 2 of the drawings. Figs. 5, 6, 7, and 8 are details hereinafter described.

Like numerals of reference indicate like parts throughout the drawings.

The sofa-frame comprises the usual opposite end pieces 1 1, the two being securely connected by the transverse base 2. This base may comprise the usual box or receptacle 3, such arrangement not forming any part of my present invention.

Mounted removably upon the transverse base 2 is a seat-section 4, and between the two end pieces and in the present instance wholly independent thereof, so as to be free to move therebetween, is the back-section 5. At their opposite meeting corners the two sections, the seat and the back, are connected, in this instance by a locking-hinge 6, the details of which I will now proceed to describe.

The locking-hinge 6 shown is the preferred form, though other styles of hinges may be substituted. In the present instance, however, it comprises the opposite leaves 7 and 8, designed in the usual manner to be secured, respectively, to the end rails of the seat and back sections. Each of these leaves has formed at its lower inner corner one member 9 of an ordinary hinge - eye. These two hinge-eye members overlap in the usual manner and are pivotally connected by means of a transverse pindle 10.

A stud 11, preferably headed, projects from the face of the hinge member or leaf 8, near the outer lower corner thereof, and loosely pivoted at a corresponding point on the face of the opposite hinge member or leaf 7, as at 12, is a stud-engaging gravity-latch 13. This latch lies across the faces of the two hinge-leaves 7 and 8 and near its free end is provided on its under side with a recess 14, designed to engage the headed stud 11 under certain conditions. The recess terminates at its inner or front end in a shoulder 15 and at its upper or outer end in a shoulder 15^a. The recess being slightly longer than the diameter of the shank of the stud, it will be obvious that the two leaves are capable of some little pivotal movement or separation before either of the recesses is brought in contact with the shank of the stud and a locking of the two leaves effected.

Pivoted to the face of the gravity-latch 13, as at 16, immediately in rear and slightly above the recess 14 of said latch, is a small gravity-pawl 17, having at its free end a recessed shoulder 18 and at the opposite side of

its pivot-point a stop-shoulder 19, designed to abut against a stop-pin 20, whereby the movement of the pawl is limited in both directions. The pawl 17 at its free end lies across the recess 14 of the latch, and its shoulder 18 is slightly beyond the shoulder 15 of the latch and, like the latter shoulder, is designed under certain conditions to engage with the headed stud 11.

10 At the outer side of the hinge there is secured in a manner hereinafter described or otherwise, as preferred, and to the end rail of the back section 5 a bracket 21. This bracket is provided in the present instance with a right-angular lug 21^b for engaging the side rail of the back-section and with a screw-receiving opening 21^a, through which a screw may be inserted into said end rail. Its opposite branches project out each side of the pin-tle 10 of the hinge, and to its front branch there is loosely pivoted, as at 22, the upper end of a laterally-swinging supporting-rod 23, the lower end of which is pivotally connected to a stud-plate 24, secured to the lower cross-rail of the end piece 1 in advance of the meeting ends of the front and back sections when said sections are arranged in sofa form. To the opposite or rear branch of the bracket 21 there is pivoted, as at 25, the upper end of a shorter companion governing-rod 26, the lower end of which is pivotally connected by a stud-plate 27 to the end piece 1. These rods are of course duplicated at each side of the sofa-bed.

15 In operation taking, for example, the article shown in Fig. 3 in order to convert the same to a bed it is first necessary to withdraw the article a short distance from the wall, against which such articles are usually located. Having done this, the operator grasps the seat at the front and draws the same forward and upward, thus raising the free end to the position shown in Fig. 2. By reason of this operation it will be seen that 20 the seat and back are elevated above and lowered in advance of their former positions upon the base 3. This elevating and advancement of the seat and back is accomplished by the governing-rod 26 operating in conjunction with the laterally-swinging supporting-rod 23, for, as will be apparent, the former rods being eccentrically pivoted with relation to the rods 23 will cause the latter to swing forward as the seat is elevated, 25 whereby the seat and back sections are caused to clear the base in their turning movement. When the parts have reached this position, they are as shown in Fig. 2. The operator continues the backward movement of the seat for a short distance, or until the shoulders 18 of the pawls 17 have engaged with the shanks of the studs 11, after which it is simply necessary to lower the seat to the position shown in Fig. 1, the pawls 17, it being 30 understood, operating in the usual manner,

and therefore serving to disengage the latches 13 from the studs. During this lowering movement it will be observed that the pawl 17, swinging on its pivot 16, will have raised the latch 13 so as to bring its recess 14 clear of the stud 11, after which the seat passing beyond the pawl the latch 13 will be released, and for the balance of the movement the lower curved edge of the latch 13 will ride loosely over the stud 11. 70

75 To return the parts to the position of a sofa, the seat-section 4 is again elevated until the inner shoulder 15 of the latch 13 engages with the stud 11, after which it is simply necessary to lower the seat-section and at the same time gently push the seat-section backward. The rods 23 and 26 coacting with these two sections will retract both the seat and back section at the same time the seat-section is lowered and the back section elevated, thus bringing the parts to the position shown in Fig. 3.

80 It will be observed that I have obviated in the construction of the end pieces 1 the usual guides employed for guiding the back-section in its movements, thus not only greatly simplifying the structure of the article as a whole and relatively cheapening the same, but also causing the article to be more sightly in that all the mechanism is hidden from view. It 85 furthermore obviates the frictional contact between the end pieces and the back-section, rendering the movement of the latter noiseless and easier. The lower ends of the laterally-swinging supporting-rods being pivoted 90 only a short distance in advance of their upper ends, it takes but the slightest effort to elevate and turn the seat and back sections forward until the supporting-rods have reached a vertical position, and when this 95 has been accomplished by reason of the presence of the rear governing-rods the two sections are balanced and may be moved in either direction with little effort, so that the remainder of the operation—that is, of advancing 100 and lowering the back and simultaneously advancing and elevating the seat is practically automatically accomplished.

105 Of course other forms of locking-hinges may be substituted for the construction of hinge herein shown and described without departing from the spirit of my invention, and, in fact, other details may be altered all within the scope of my claims.

110 Having thus described my invention, what I claim as new, and desire to secure by Letters Patent, is—

115 1. The combination in a sofa-bed, of opposite end pieces, a transverse connecting-base, a seat and a back section mounted between the end pieces and independent of the same, a locking-hinge connecting the seat and back sections at their meeting corners, a bracket arranged at each end of and secured to the back-section and extending at 120

opposite sides of the meeting edges of the two sections, front and rear suspension-rods connected to the brackets at each side of the pintle of the locking-hinge and at their lower ends pivotally connected to the framework at opposite sides of the meeting edges of the front and back sections.

2. The combination, in a sofa-bed, of the opposite end pieces, the transverse connecting-base, a seat-section mounted movably on the latter, a back-section arranged between the end pieces, opposite locking-hinges connecting the two sections, and oppositely-inclined suspension-rods upon which said sections are designed to move, said rods having their lower ends connected to the framework at opposite sides of the meeting edges of the front and back sections.

3. The combination, in a sofa-bed, of opposite end pieces, a transverse connecting-base, seat and back sections, opposite locking-hinges connecting the two sections at their meeting edges, front and rear supporting-rods, the former being longer than the latter, means for connecting said rods at their lower ends, to the framework of the article, and means for connecting the upper ends of the rods to the seat and back sections at opposite sides of the pintles of said locking-hinges.

4. In a sofa-bed, the combination, of the opposite end pieces, the transverse connect-

ing-base, the seat and back sections independently movable between the end pieces, the opposite locking-hinges connecting the meeting ends of the said sections, brackets secured to the back-section and overlapping the front section at the meeting edges of said sections, suspension-rods connected to the opposite ends of said brackets, and means for connecting said rods at their lower ends to the framework.

5. In a sofa-bed, the combination, of the opposite end pieces 1, the transverse base connecting the two, the seat-section 4 and 45 back-section 5 independent of the end pieces, the opposite locking-hinges connecting the sections 4 and 5 at their meeting edges, the opposite angular brackets 21 secured to the end rails of the back-section and overlapping 50 the end rails of the seat-section, and the suspension-rods 23 and 26 pivotally connected at their upper ends to the front and rear ends of the brackets and at their lower ends pivotally connected to the framework, as at 24 55 and 27.

In testimony whereof I have signed my name to this specification in the presence of two subscribing witnesses.
